UNITED STATES PATENT OFFICE

109,851

DESIGN FOR A PLATE FOR MOLDS FOR HARD RUBBER GOODS

Byron W. Meredith, Morrisville, Pa.

Application September 3, 1937, Serial No. 71,451

Term of patent 14 years

To all whom it may concern:

Be it known that I, Byron W. Meredith, a citizen of the United States, residing at Morrisville, in the county of Bucks and State of Pennsylvania, have invented a new, original, and ornamental Design for a Plate for Molds for Hard Rubber Goods, of which the following is a specification, reference being had to the accompanying drawing, forming part thereof.

Figure 1 is a top perspective view of the plate showing my new design; and

Figure 2 is an inside view thereof.

What I claim is:

The ornamental design for a plate for molds for hard rubber goods, as shown.

BYRON W. MEREDITH.
